UNITED STATES PATENT OFFICE.

IVAN S. HEILBRUN, OF NEW YORK, N. Y.

FOUNTAIN-PEN STAND.

Application filed January 14, 1927. Serial No. 161,085.

This invention relates to the class of articles commonly known as "fountain pen desk sets" and more particularly to a stand or holder for a fountain pen or the like.

5 The object of this invention is to provide a self-righting stand which is so constructed that when tilted from its normal upright position it will automatically return to that position.

10 The accompanying drawings illustrate a preferred embodiment of my invention in which:—

Figure 1 is a vertical section of the stand with a fountain pen held therein,

15 Fig. 2 is a bottom plan view thereof, and,

Fig. 3 is a side elevation of a modification, on a smaller scale.

20 The stand comprises a hollow base 1, having a hollow tubular neck 2, suitably secured thereto and projecting upwardly therefrom either vertically or at a convenient angle. The inner surface of the neck preferably tapers slightly outwards and terminates in a flare 3. The neck serves as a holder for the fountain pen 4, the tapered pen section 5 of which engages with the tapered inner surface of the neck, as shown in Fig. 1, so as to prevent the pen from being inserted too far into the base with possible injury to the penpoint.

25 In its preferred embodiment, the base is of substantially oblate spheroidal shape, although I do not limit myself to this particular configuration.

30 The base may be made of pyroxylin, glass, metal, or other suitable material and is preferably made of two halves, cemented or otherwise secured together so as to form a rib or flange 7 extending circumferentially around the joint. The lower half has a flattened bottom portion 8, preferably formed with a re-

cess 9, and upwardly and outwardly curved walls 10 that provide rocking surfaces on which the base may be tilted or rocked. The base is suitably weighted in its interior with a layer of cement 11 or other weighting material so that when tilted from its upright position it will automatically return thereto.

45 The flattened portion 8 provides a rest on which the base may stand in upright position upon a desk or other surface, and the peripheral rib or flange 7 prevents the base from being overturned or tilted too far from the vertical.

50 By grasping the pen 4 in one hand and tilting the base, the pen can be readily removed from the base which will then automatically right itself. Inasmuch as the operation of removing or replacing the pen may be conveniently performed with one hand, the other hand is left free for use for other purposes.

55 Various modifications in the details of the construction herein described may be made without departing from the scope of the invention as defined in the claim.

60 What I claim is:—

65 A self-righting stand for writing implements, including a hollow body having a lower portion and an upper portion, a connection for said portions to secure same together, said connection extending outwardly from the body so as to form a peripheral projection adapted to engage with the surface of a support to thereby restrict tilting movement of the body, a weight within and secured to the bottom of the lower portion, and a tubular 70 neck secured to and projecting outwardly from the upper portion and formed to receive a writing implement therein.

IVAN S. HEILBRUN.
